CLAIM

The ornamental design for a garden shoe, as shown and described.

DESCRIPTION

FIG. 1 is a front, right, and top perspective view of a garden shoe, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a part of a heelpiece; and,

FIG. 10 is a partial enlarged view of an area labeled 10 in FIG. 2 comprising a part of a sole.

A garden shoe for a right foot is a mirror image of the garden shoe for a left foot as shown in FIGS. 1 to 8.

1 Claim, 10 Drawing Sheets
